ELECTRO RESPONSIVE RECORDER

Howard C. Lindemann, Westbury, N. Y.

Application November 15, 1956, Serial No. 43,779

Term of patent 7 years

(Cl. D26—14)

Fig. 1 is a front perspective view of an electro responsive recorder, showing my new design; and
Fig. 2 is a rear perspective view thereof.

I claim:

The ornamental design for an electro responsive recorder, as shown.
